UNITED STATES PATENT OFFICE.

ARLON LITTLEFIELD, OF PROVIDENCE, RHODE ISLAND, ASSIGNOR TO NEW ENGLAND BUTT COMPANY, OF PROVIDENCE, RHODE ISLAND, A CORPORATION OF RHODE ISLAND.

CARRIER FOR BRAIDING-MACHINES.

1,172,719.

Specification of Letters Patent.

Patented Feb. 22, 1916.

Application filed February 19, 1915. Serial No. 9,273.

To all whom it may concern:

Be it known that I, ARLON LITTLEFIELD, a citizen of the United States, and resident of the city of Providence, in the county of Providence and State of Rhode Island, have invented certain new and useful Improvements in Carriers for Braiding-Machines, of which the following is a specification.

This invention relates to carriers for 10 braiding machines more particularly of the class designed for braiding wire or other similar heavy work, and the object of the invention is to provide a carriage having its reel or spool on which the braiding material is carried located adjacent its base for 15 the purpose of keeping the weight as low as possible so as to minimize the action of centrifugal force upon the rapidly traveling carrier and so prevent excessive wear on 20 the parts.

A further object of the invention is to provide springs instead of heavy weights for exerting tension on the material while braiding and so again reduce the weight of an 25 operating carrier.

It is found in practice that a carrier employed in the laying of wire armor onto a core, owing to its necessarily heavy construction, is considerably affected by the action 30 of centrifugal force upon it in traveling rapidly along the sinuous course of its race-way and that the wire reel with its heavy load should be located near the bottom of the carrier so as to place the center of gravity as low as possible, therefor, to accomplish 35 this instead of mounting this reel at the top as is the case in some types of carriers I have located the same adjacent the base, and have also minimized the size of 40 the tension member which is above the reel, by employing springs for obtaining the comparatively high degree of tension on the wires to be braided.

With these and other objects in view, the 45 invention consists of certain novel features of construction, as will be more fully described, and particularly pointed out in the appended claims.

In the accompanying drawings: Figure 50 1— is a front elevation of my improved carrier. Fig. 2— is a central sectional side elevation of this carrier. Fig. 3— is a perspective view of the latch or let-off pawl which engages the teeth of the reel ratchet.

55 Referring to the drawings 10 designates

the base of the carrier which travels upon the top plate (not shown) of the machine and 11 and 12 designate the standards extending upwardly from this base. The lower portion of these standards is spaced apart 60 a little wider than their upper portion, and in this lower space is rotatably mounted the reel or spool 13 on the bearing pin 14 which passes through the opposite standard and whose axis is set substantially at right 65 angles thereto. On one side of and connected to this reel is a ratchet wheel 15 for the purpose presently described. On one of the standards is mounted a pawl 16 adapted to slide vertically on the screw 17 with its 70 lower end engaging the teeth of the ratchet 15. Said pawl is provided with an extension 18 guided by a flange or standard 12, to hold the pawl to its engaging position, and to the upper end of this pawl is connected a 75 vertical rod 19 having an upper bearing 20 in the frame and to this rod is connected an operating finger 21. A spring 22 acts between the frame and this finger to normally press this pawl into engagement with the 80 ratchet teeth. A factor in the reduction of the operating weight of the carrier to the minimum is the provision of a tension member 23, which is shown as being mounted to slide vertically on the guide rods 24. This 85 weight is formed very light and is pressed downward under tension of the coil springs 25, and on this weight is mounted a comparatively large idler pulley 26. On the upper portion of the standards is a cross 90 bar 31 on which is mounted a large idler 27 considerably off-set to overhang this frame in order to obtain the necessary angle of lead for the wire from the reel below. A second guide roll 28 is located on the other 95 side of the frame to conduct the wire through the guide eye 29 which is located in the pivoted yoke 30 to swing and accommodate the varying direction of lead.

In the operation of my improved carrier, 100 the wire from the reel is carried up over the large pulley 27 down around the pulley 26 of the member 23 and then up over the pulley 26 through the guide eye 29 to the core onto which the armor is braided.

The degree of tension is controlled by 105 the stiffness of the springs 25 upon the member 23, and when a greater tension is required, the rods 24 are removed and stiffer springs are placed upon them. When the 110

desired tension on the wire has been reached the member 23 is raised by the taking up of the loop of wire around the pulley 26, raising the tension member until it engages 5 and raises the pawl finger 21 which at once releases the reel to unwind more wire.

The essential feature of this invention is that the weight in the carrier is as low down or as near its bottom portion of the carrier 10 as possible so as to reduce and minimize the action of centrifugal force upon the upper portion and so reduce the wearing effect of the carrier and also the walls of the guides and raceways in which it travels.

15 I claim:

1. In a braider, a carrier comprising a base portion, a pair of standards extending upwardly from said base, a reel located near the lower portion of said standards 20 with its axis at a right angle to said standards, a tension member slidably supported above said reel, a ratchet wheel on the reel, a let-off pawl slidably supported by one of said standards and engaging said ratchet, 25 and a controlling member for said pawl guided by said standard, said controlling member having a portion overhanging said tension member and in the path of movement thereof.

30 2. In a braider, a carrier comprising a base portion, a pair of standards extending upwardly from said base, a reel located near the lower portion of said standards with its axis at a right angle to said standards, a 35 tension member slidably supported above said reel, a ratchet wheel on the reel, a let-off pawl slidably supported by one of said standards and engaging said ratchet, a rod attached to said pawl, a guide for said rod, 40 and an operating finger attached to said rod

and having a portion extending into the path of movement of the tension member, and means for yieldingly holding said pawl to its work.

3. In a braider, a carrier comprising a 45 base portion, a pair of standards extending upwardly from said base, a reel located near the lower portion of said standards with its axis at a right angle to said standards, a tension member slidably supported above 50 said reel, a ratchet wheel on the reel, a let-off pawl slidably supported by one of said standards and engaging said ratchet, a controlling member for said pawl guided by said standard, said controlling member having a portion overhanging said tension member and in the path of movement thereof, and means for guiding the lower end of said pawl.

4. In a braider, a carrier comprising a 60 base portion, a pair of standards extending upward from said base, a reel located near the lower portion of said standards with its axis at a right angle to said standards, a spring pressed tension member slidably 65 supported above said reel, a ratchet wheel on the reel, a let-off pawl engaging said ratchet, an operating rod for said pawl, an operating finger attached to said rod and having a portion extending into the path of movement of the tension member, and a spring acting against said finger to hold said pawl to its work.

In testimony whereof I affix my signature in presence of two witnesses.

ARLON LITTLEFIELD.
